(57) **CLAIM**

The ornamental design for an electric bicycle, as shown and described.

DESCRIPTION

FIG. 1 is a front, right and top perspective view of an electric bicycle, showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion of FIG. 1 thereof;

FIG. 10 is another enlarged view of portion of FIG. 1 thereof;

FIG. 11 is yet another enlarged view of portion of FIG. 1 thereof;

FIG. 12 is an enlarged view of portion of FIG. 2 thereof;

FIG. 13 is another enlarged view of portion of FIG. 2 thereof; and,

FIG. 14 is yet another enlarged view of portion of FIG. 2 thereof.

The dot-dash broken lines indicate the boundaries of the enlarged views and are used for annotative purposes only. They do not limit or define the scope of the claimed design.

1 Claim, 14 Drawing Sheets
